UNITED STATES PATENT OFFICE.

JOHAN VIKTOR BLOMQUIST AND KARL FREDRIK WESSBLAD, OF STOCKHOLM, SWEDEN.

APPARATUS FOR INDICATING THE ELONGATION OF TUBULAR ELEMENTS COMBINED WITH SAFETY DEVICES IN STEAM GENERATORS.

Application filed October 12, 1923, Serial No. 668,227, and in Sweden October 28, 1922.

Our invention is directed particularly to improvements in such steam generators in which the steam is generated in rotating or non-rotating tubular elements containing a rotating layer of water. In steam generators of this type the steam generating tubular elements must be journaled in such a way on account of their expansion by the heat that no stresses or deformations arise in the same by such expansion. The tubular elements, therefore, are generally supported in their bearings in such a way that they are held fast in their axial direction at one end while they are permitted to freely expand at the opposite end.

According to the present invention this expansion of the tubular elements is utilized partly for determining whether an extensive deposit of scale has taken place in the tubular elements, in which case on account of the reduced transference of heat they will assume a higher temperature and a greater length than when they are clean, and partly, when a tubular element by accidental shortness of water also assumes a higher temperature and an abnormal length, for making it possible for the attendants clearly to observe such dangerous expansion and in time reduce the steam pressure, for instance by easing the safety valve, thus preventing the danger of explosion.

For this purpose a pointer or index is provided at the free end of the tubular elements, said pointer being arranged in such a way that it is moved by said element when expanding and indicates the elongation of the tubular element on a scale. According to the invention this pointer is also arranged in such a way that it causes the steam pressure to be automatically lowered at an incidental shortness of water either by closing an electric circuit as soon as the elongation reaches a predetermined value, whereby an electromotor in said circuit is acted upon to ease the safety valve by means of a suitable mechanism, or by directly opening a special valve, through which the steam in the tubular element or the generator escapes.

The invention is illustrated in the accompanying drawings in which Fig. 1 is a longitudinal section through a rotary tubular element of a steam generator having a pointer in the shape of a bell crank lever

and an electric easing device for the safety valve. Fig. 2 shows a similar view with an axially movable pointer adapted directly to open a special valve for letting out the steam.

Fig. 3 is a transverse cross section through a plurality of tubular elements arranged in a common furnace.

Fig. 4 is a horizontal sectional view of the common furnace taken above the plurality of tubular elements therein.

In Fig. 1 the rotary tubular element is prevented from moving axially by means of the bearing 2 while the opposite end of said element is freely movable in the bearing 3. A pointer 4 shaped as a bell crank lever is resting against an edge on the end of the tubular element and said pointer 4 is made to travel over a scale 5 thus indicating the elongation of the tubular element. If the latter expands over a predetermined limit on account of too extensive deposit of scale or of shortness of water, the pointer will close the electric contact 6 thereby starting the electromotor 7 which latter for instance by means of a screw 8 and a crank 9 acts upon a safety valve 10 for easing the same, said safety valve being connected with the steam space of the generator. It is obvious that the automatic action upon the safety valve may be dispensed with, as the safety valve, of course, may be acted upon by hand according to the deflection of the pointer.

The form shown in Fig. 2 comprises a pointer movable in the longitudinal direction of the tubular element and adapted directly to open a special valve, through which the steam escapes at incidental shortness of water in the tubular element 11. The latter is held fast at one end by the bearing 12 so that it cannot move axially, while the opposite end of the same is free to slide in the bearing 13. A pointer 14 rests against an edge on the tubular element and indicates the elongation of the same on a scale 15. If the tubular element expands unduly on account of deposit of scale or shortness of water the pointer will open the valve 16 connected with the steam space of the generator whereby the steam escapes and the steam pressure is reduced. Also in this arrangement the automatic action upon the safety valve may be dispensed

with and the safety valve may be operated by hand in accordance with the deflexion of the pointer.

In Figs. 1 and 2 the invention is shown adapted to steam generators consisting of a plurality of rotary tubular elements 1, adapted to be driven by meshing gears 20, by a prime mover 21, the elements being all mounted in a common furnace 22, but it may be used in a similar manner for steam generators consisting of fixed tubular elements containing a rotary layer of water.

The device for automatically reducing the steam pressure may of course vary in several ways, the essential feature of the invention consisting of a device whereby the expansion of the steam generating tubular elements on account of an increase of temperature may be observed, so that hereby necessary measures to ensure safety may be taken by hand or automatically.

Having thus described our invention what we claim and desire to secure by Letters Patent is:—

1. A rotary steam generator in which steam is generated in a plurality of tubular elements each containing a rotary layer of water, comprising, a furnace, a plurality of tubular elements mounted in the furnace, means to produce a rotary layer of water in each element, each element having means for keeping one end of the tubular element in a fixed position to prevent it from moving axially, means for supporting the other end to permit this latter end to freely expand in an axial direction, an indicator coacting with said latter end of the tubular element, and means for transmitting the movement of axial expansion of said element to the indicator, to measure the axial expansion of the tubular element thereby.

2. A rotary steam generator in which steam is generated in a plurality of tubular elements each containing a rotary layer of water, comprising, a furnace, a plurality of tubular elements mounted in the furnace, means to produce a rotary layer of water in each element, each element having means for keeping one end of said tubular element in a fixed position to prevent it from moving axially, means for supporting the other end to permit this latter end to freely expand in an axial direction, an indicator coacting with said latter end of the tubular element, means for transmitting the movement of axial expansion of said element to said indicator, and means combined with the indicator for automatically reducing steam pressure within the tubular element upon reaching the safety limit of axial expansion of the element.

3. A rotary steam generator in which steam is generated in a tubular element containing a rotary layer of water, comprising

a furnace, a tubular element mounted in the furnace, means to position a rotary layer of water in the element, means for keeping one end of the element in a fixed position to prevent it from moving axially upon elongation due to heat applied thereto, means for supporting the other end of the element to permit the element at this latter end to freely expand in an axial direction, an indicator coacting with the free end of the tubular element, and transmission means interposed between the free end of the tubular element and the indicator, so that a measure of expansion of the tubular element is indicated by the indicator.

4. A rotary steam generator in which steam is generated in tubular elements each containing a rotary layer of water, comprising a furnace, a plurality of tubular elements mounted in the furnace, means to produce a rotary layer of water in each element, means for preventing axial displacement of each of the rotating elements at the one end of the same, means for supporting the other end of each of said elements so that each element can freely expand in axial direction at this latter end, an indicator coacting with the free end of each of the tubular elements, transmission means interposed between the free end of each tubular element and the corresponding indicator, a safety valve for each of the tubular elements, and controlling means for each valve, said last mentioned means being combined with the corresponding indicator for easing the valve at the safety limit of axial expansion of the corresponding tubular element.

5. A rotary steam generator in which steam is generated in a plurality of tubular elements each containing a rotary layer of water, comprising, a furnace, a plurality of tubular elements mounted in the furnace, means to produce a rotary layer of water in each element, each element having means arranged at one end of said element to prevent the same from moving axially, means supporting the other end to permit the element to freely expand in an axial direction at this latter end, a movable indicator, transmission means for transmitting the movement of axial expansion of the tubular element to said indicator, a safety valve communicating with the tubular element, controlling means for said valve, the controlling means being combined with the indicator and acting in conformity with the movements of the same for easing the valve at the safety limit of axial expansion of the tubular element.

In testimony whereof, we have signed our names to this specification.

JOHAN VIKTOR BLOMQUIST.
KARL FREDRIK WESSBLÅD.
